UNITED STATES PATENT OFFICE.

JOSEPH M. MERROW, OF HARTFORD, CONNECTICUT.

FEEDING MECHANISM FOR SEWING-MACHINES.

1,074,968.

Specification of Letters Patent.

Patented Oct. 7, 1913.

Application filed November 3, 1910. Serial No. 590,487.

To all whom it may concern:

Be it known that I, JOSEPH M. MERROW, a citizen of the United States, residing in the city and county of Hartford, State of Connecticut, have invented certain new and useful Improvements in Feeding Mechanisms for Sewing-Machines; and I do hereby declare the following to be a full, clear, and exact description of the same, reference 5 being had to the accompanying drawings, forming a part of this specification, and to the characters of reference thereon.

This invention relates to feeding mechanism of the type commonly known as a differential feed, such feeding mechanism being provided with two feed dogs or work engaging elements each actuated either wholly or partially independently of the other, and the invention consists in peculiar constructions and combinations hereinafter pointed out and claimed.

Sewing machines, especially those of the overseaming type, are often provided with a differential feed when the machines are used on knit goods or other material liable to stretch or pout at its edge. The differential feed is designed to obviate the stretching effect, and is arranged to cause one feed dog (located in advance of the needle) to feed the goods up to the needle or point of overseaming, faster than the said goods are fed away from the needle by a second feed dog (arranged to operate in rear of the needle) and thus the goods are slightly condensed or gathered at the edge, near the point of overseaming.

In a machine fitted up with differential feeding mechanism as heretofore made, there is a tendency when operating upon heavy material, such as sweater goods and the like, for the goods, as they are pushed along by the forward feed dog, to slide over the rear feed dog and then pass out of the machine more rapidly than at the feeding rate of the rear feed dog and, under such conditions the edge of the goods will be stretched or pouted.

The invention has for its particular object the improvement of feeding mechanism of the type described to overcome the objection just recited.

These improvements are shown and described as particularly applicable to overseaming machines of the well known Merrow type, which may be either unprovided with trimming mechanism as is the case

with the machine shown in Patent No. 591,049 issued October 5, 1897, to Joseph M. Merrow, or having trimming mechanism as shown in the Patent No. 733,760 issued July 14, 1903, to William H. Stedman.

The accompanying drawings illustrate an embodiment of these improvements, in connection with a partially illustrated trimming and overseaming machine having a differential feeding mechanism, corresponding in its general characteristics with that for which an application for Letters Patent Serial No. 473,567 was filed January 21, 1909, by William H. Stedman, and characteristic features only of which will be described herein.

In the drawings—Figure 1 is an end elevation of these improvements in connection with a partially illustrated trimming and overseaming machine. Fig. 2 shows in perspective, a portion of the feeding mechanism detached from the machine. Fig. 3 is an elevation of some of the elements of the Fig. 1, as viewed from the opposite direction. Fig. 4 is a view on a somewhat larger scale than the preceding figures, illustrating in plan portions of the machine adjacent the needle plate and showing a piece of goods upon the said needle plate, the edge of which piece of goods is undergoing the process of being trimmed and overseamed. Fig. 5 is a view showing the lower portion of the presser foot and many elements of the Fig. 4 in elevation, but showing the needle plate in section.

Like reference characters in the several figures indicate the same parts.

The number 10 denotes the frame of the machine, 11 the head, 12 the needle plate support and 13 the needle plate. A spring depressed presser foot 14 is provided with a lifting lever 17. The main shaft 20 and an upper shaft 21 have gear connection and the usual needle driving mechanism is provided having connection with the shaft 21 whereby the rotation of the shaft effects the oscillation of the needle carrier 23 and causes the needle 25 to reciprocate through the needle plate 13. Suitable stitch forming implements or loopers coöperate with the needle to effect the formation of overseam stitches, this feature not demanding a complete illustration or description in connection with these improvements.

In the feeding mechanism there are two feed bars 30 and 40 that are located side by

side and each at its rear end is recessed to receive respectively the blocks 32 and 42 which are axially mounted on a fixed pin 26 and which slidably support the feed bars 5 that the latter may have both endwise and pivotal movements with reference to the said pin. The feed bars 30 and 40 are also slidably supported near their front ends, the bars being respectively recessed to receive 10 eccentric encircling blocks 34-44 upon which the said sliding movements may take place. The blocks 34-44 are actuated by eccentrics (not shown) on the main shaft 20 so that, upon the rotation of the shaft, the feed bars are rocked vertically with reference to the pivotal supporting pin 26. To slide the feed bars horizontally there are mounted side by side upon the shaft 20 two eccentrics 55-56 from which links 60-70 15 effect connection with the feed bars 30 and 40, the said links at their forward ends encircling the eccentrics and at their rear ends being pivotally secured to their respective feed bars by the studs 61 and 71. Upon the rotation of the shaft 20 the eccentrics 55 and 20 56 through the links 60 and 70 effect a positive horizontal reciprocation of the feed bars 30 and 40 which, combined with the already described vertical rocking of the said bars 25 causes the forward ends to travel with a "four motion" movement. The feed bars 30 and 40 are respectively provided at their forward ends with the feed-dogs 35 and 45 having goods engaging teeth 35^A and 45^A, which are adapted to project upward 30 through openings 13^A in the needle plate 13.

The overseaming machine shown in the drawings is of the same type as that shown and described in the Patent No. 733,760 already mentioned, a lower stationary cutter 80 being supported beneath the needle plate 13 coöoperating with an upper moving cutter 81.

The front tooth of the rear feed dog 45, at 45 its forward end, is made with a corner or edge 45^C to obstruct or hold back the goods from being fed at that point faster than the movement of the rear feed dog would carry them along and thus facilitate the condensing or gathering of the goods. The front tooth is preferably made with a flat top surface 45^B which acts as a clamp against the presser foot 14 to further hold the goods, and the rear edge 45^D of the front tooth acts 50 as a feeding tooth and thus in these particulars, for such purposes, the form of tooth shown is preferable to a tooth of the usual form, reversed. The rear feed dog 45 is also provided with an extra feed surface 55 which may consist of a single tooth 45^E located just beyond the needle plate finger 13^B (around which finger the stitches are formed) for the purpose of carrying along the chain when the machine is "chaining" 60 without fabric, as well as to assist in feed-

ing the extreme edge of the fabric when the latter is present.

When the machine is to operate upon heavy goods, it is desirable that there be increased space or more than the usual space vertically for the condensation or gathering of the edge of the goods between the feed dogs and to provide this space the presser foot is recessed as at 14^A on its bearing face between the points of coöperation with the 75 feed dogs.

The upper face of the needle plate 13 is preferably roughened or serrated as at 13^B as commonly practised to prevent accidental backward slipping of the material upon the 80 needle plate. The edge support 13^C secured to the needle plate support 12 is located at the edge of the needle plate 13 at the side of the forward feed dog and in proximity with the cutters 80 and 81 and is provided with 85 coarse teeth designed to engage the goods under the presser foot and prevent any backward push of the goods at the edge thereof likely to be caused by the overseaming or trimming operations or both. 90

Having thus described my invention, what I claim as new and desire to secure by Letters Patent of the United States is:-

1. In combination, in a sewing machine, a differential feeding mechanism including two feed dogs one of which is provided with a tooth having a fabric engaging portion arranged reversely to the feeding teeth to engage and retard the fabric pushed forward by the companion feed dog, a presser foot coöoperating with the feed dogs and means for actuating the said feed dogs. 95

2. In combination, in a sewing machine, a differential feeding mechanism including two feed dogs one of which is provided with 105 a tooth having a fabric engaging portion arranged reversely to the feeding teeth to engage the goods fed thereto by the companion feed dog and facilitate the gathering or condensing thereof of the goods and also with a 110 fabric engaging portion substantially corresponding to the feed teeth to assist in feeding the goods, a presser foot coöoperating with the feed dogs, and means for actuating the feed dogs. 115

3. In combination in a sewing machine, a differential feeding mechanism including a plurality of feed dogs each having a feeding surface, a presser foot having a recessed sole with which the said feeding surfaces co-operate, means interposed between two of the feeding surfaces and partaking of the movements thereof and coöperating with the presser foot sole whereby the gathering or condensing of the goods is facilitated, and means for actuating the feed dogs. 120

4. In combination, in a sewing machine, a differential feeding mechanism including two feed dogs one arranged to retard the feeding action of the other, the retarding 130

- dog having a tooth having a fabric engaging edge arranged reversely with relation to the feeding teeth and a surface extending in a plane substantially parallel with the 5 plane of movement of the goods, a presser foot coöperating with the feed dogs and means for actuating the feed dogs.
5. In combination, in a sewing machine, a differential feeding mechanism including 10 two feed dogs one of which has a tooth provided with an edge at its forward end to engage the goods and retard the feeding action of the companion feed dog and with a similar edge at its opposite end to assist in 15 feeding the goods, a flat surface intermediate the edges, a presser foot coöperating with the feed dogs and adapted to clamp the goods between itself and the flat surface, and means for actuating the feed dogs.
- 20 6. In combination, in a sewing machine, a differential feeding mechanism including two feed dogs, a presser foot having a single goods engaging sole coöperating with both feed dogs and having said sole recessed between the points of coöperation with the 25 feed dogs and means for actuating the said feed dogs.
7. In combination, in a sewing machine, a feeding mechanism including two feed 30 dogs and a coöperating presser foot, one feed dog having a retarding tooth provided with a flat surface between which and the presser foot the goods may be clamped to retard the feeding action of the companion 35 feed dog, the said presser foot having a single goods engaging sole recessed between its points of feed dog coöperation and forward of the retarding tooth to provide space for condensing or gathering the goods and 40 means for actuating the feed dogs.
8. In combination, in a sewing machine, a feeding mechanism including two feed dogs, one located forward of the other, and a coöperating presser foot, the forward feed 45 dog having teeth for feeding the goods and the rear feed dog having a feeding surface including a tooth provided with a flat goods engaging surface and two sharp edges arranged transversely to the direction of the 50 machine's feed at each end of the said surface, whereby the goods will be held in fixed relation to the said rear feed dog during the feeding movement thereof, the said presser foot having a single goods engaging 55 sole recessed to provide space for the gather-

ing or condensing of the goods forward of the holding tooth on the rear dog, and means for actuating the feed dogs.

9. In combination with overseaming mechanism, a gathering feeding mechanism including two differentially acting feed dogs one of which is provided with a tooth having a fabric engaging portion arranged reversely to the direction of feed for checking the travel of the goods from the companion feed dog, the said first named feed dog being also provided with teeth for feeding the goods independently of the said companion feed dog, a presser foot coöperating with the feed dogs, means for actuating the overseaming mechanism and means for actuating the feeding mechanism.

10. In combination with overseaming mechanism, a gathering feeding mechanism including two differentially acting feed dogs one of which is provided with a tooth having a fabric engaging portion arranged reversely to the direction of feed for checking the travel of the goods from the companion feed dog, the said first named feed dog being also provided with teeth for feeding the goods independently of the said companion feed dog, a presser foot coöperating with the feed dogs and having a single goods engaging sole that is recessed between its points of coöperation to accommodate the gathering or condensing of the goods, means for actuating the overseaming mechanism and means for actuating the feeding mechanism.

11. In combination, in an overseaming machine including stitch forming mechanism and trimming mechanism, a gathering feeding mechanism including two differentially acting feed dogs arranged one in front of the other, the forward feed dog having a toothed surface operating in advance of the point of trimming, and the rear feed dog having a toothed surface and an element operating in rear of the needle, the said element having a smooth flat surface and two sharp edges coöperating with the toothed surface of the rear feed dog to limit the feeding of the goods to the feeding movement of the rear feed dog, substantially as and for the purposes described.
